MANUFACTURE OF THREAD OR THE LIKE

Walter F. Knebusch and Alden H. Burkholder,
Cleveland, Ohio, assignors to Industrial Rayon
Corporation, Cleveland, Ohio, a corporation of
Delaware

Original application February 18, 1935, Serial No.
7,114. Divided and this application March 26,
1936, Serial No. 71,019

3 Claims. (Cl. 18—8)

This invention relates to apparatus for the manufacture of thread or the like.

The present application is a division of a prior application, Serial No. 7,114, filed February 18, 5 1935, by Walter F. Knebusch and Alden H. Burkholder, in which is shown, described, and broadly claimed a form of apparatus suitable for the continuous manufacture of thread or the like. On such apparatus, thread or the like, such, for example, as viscose artificial silk thread, is extruded 10 into a coagulating bath contained in a trough, from which it is withdrawn by a suitable thread-advancing thread store device disposed generally above the trough. From the thread-advancing 15 thread store device the thread or the like is passed downward to a series of vertically spaced thread-advancing thread store devices disposed in stepped arrangement on which the thread or the like is subjected to suitable processing treatments, 20 the thread or the like being thereafter collected in package form by suitable collecting means. The present application is directed to features shown and described, but not specifically claimed, in said prior application.

25 In the accompanying drawings, forming a part hereof, Figure 1 is an end elevation of a complete machine of the kind described in said prior application, parts being omitted for the sake of clearness. Figure 2 is an elevation on a larger scale of 30 a portion of the machine, corresponding generally to the upper left hand portion of Figure 1 and including the coagulating bath and associated apparatus. Figure 3 is an elevation, on an enlarged scale, corresponding to the upper portion 35 of Figure 2. Figure 4 is a side elevation, on the same scale as Figure 2, of the upper portion of the right hand face of the machine in Figure 1 as seen from line 4—4 of Figure 1, parts being broken away or omitted for simplicity of illustration. Figure 5 is a longitudinal sectional elevation 40 on an enlarged scale and corresponding generally to line 5—5 of Figure 6 of a reel which may be used as the thread-advancing thread store device in apparatus embodying the invention. Figure 6 is an end elevation of the reel of Figure 5. In the drawings, like reference characters refer 45 to like parts throughout.

While the apparatus of the present invention 50 is capable of use in or in connection with the manufacture of various kinds of thread or the like, as, for example, artificial silk thread produced by the viscose, cuprammonium, nitrocellulose, cellulose acetate and similar processes, for 55 convenience it will be described as applied to the

manufacture of multiple filament viscose artificial silk thread.

Referring first to Figures 1 and 2, the thread is formed by extrusion of the viscose from the spinning nozzle 1 into a coagulating bath contained in the trough 2, being then led over guides 3, 4 to and along a suitable self-threading thread-advancing reel 5 from which it passes to any suitable number of like self-threading thread-advancing reels 5a to 5i, upon which are performed any desired processing steps. The latter may be of cantilever construction; that is, they may be supported and driven from one end only, the other end being unobstructed by anything impeding the discharge of the thread. The 15 thread is led from the last self-threading thread-advancing reel 5i to a collecting device, such as cap-twister 7.

The production of each multiple filament thread requires a complete series of such parts, 20 hereinafter referred to as a unit, including a spinning nozzle, a reel disposed generally above the trough containing the coagulating bath, a series of reels in numbers sufficient to enable the necessary or desirable steps to be performed upon the 25 thread, and the collecting device. However, as is usual in this art, a given machine may be built to provide for the simultaneous production of a multiplicity of threads, so that the machine includes a series of such units located and arranged 30 with relation to each other in such a manner as to enable the parts to be conveniently accessible for inspection, manipulation or repair. Thus in the instant machine the units are disposed along the longitudinal trough 2 containing the coagu- 35 lating bath, said trough being disposed at the upper portion of the machine with the processing reels 5a to 5i disposed below the trough 2. The machine as a whole, as can be seen from Figure 1, is of double-sided construction, having two oppo- 40 sitely disposed, inclined banks of reels, with a separate trough for each bank of reels.

As in conventional practice, spinning nozzles 1 are supported by mass tubes 35, a plurality of such mass tubes 35 being supported on an apron 45 extending along the working face of the trough, from which working face access by an operator on platform 9 may be had to the spinning nozzles for inspection, replacement, starting of the thread, etc. The reels 5, to which the threads pass 50 from corresponding spinning nozzles 1, are positioned generally above the trough 2 with their unsupported ends extending away from the working face of the trough and with their axes parallel to each other, normal to the longitudinal axis of 55

the trough, and disposed in a common horizontal plane. In the apparatus shown, no processing medium is applied to the thread while it is stored on reel 5, this reel thus providing an interval for 5 further coagulation of the thread before it passes to the next reel 5a.

Each reel 5 is supported in the desired position by a downwardly extending bracket 102 fastened to the frame member 142 of the machine, which frame member is disposed above and parallel to trough 2. Each reel 5 is rotated, as shown in Figure 3, by a sprocket 58 fastened to the drive shaft 59 of the reel, sprocket 58 being rotated by a chain 57 driven from sprocket 15 56 mounted on a short shaft 49. Each shaft 49 is driven from a horizontal drive shaft 43, which extends longitudinally of the machine, by means of a helical gear 47 mounted on shaft 43 meshing with helical gear 48 loosely rotatable upon 20 the shaft 49. Helical gear 48 is provided with a clutch member 50 cooperating with a clutch member 51 splined to the shaft 49 and having a grooved collar 52 in the groove of which is a fork 53 of a rod 54 connected to one arm of a 25 bell crank lever 55. Figure 3 shows the clutch members 50, 51 in engagement, so that shaft 49 is rotated by shaft 43.

The shaft 43 is driven by a gear 46 mounted thereon meshing with a gear 45 which is mounted 30 on shaft 41 fixed on a bracket 42 pivoted to turn about a shaft 43 and held in any adjusted position by a cap-screw 44 passing into the frame through a curved slot in said bracket. Shaft 41 also carries a gear 40 fixed for rotation with 35 gear 45 which is driven by a gear 39 mounted for rotation with the short shaft 38. By turning the bell crank lever 55 clockwise as seen in Figure 2 or 3, the corresponding clutch may be disengaged to stop the rotation of the corresponding reel 5, and, at any time, by loosening the cap-screw 44 and swinging arm 42 to the right the driving gearing may be disengaged. By substitution of a gear of different size for 40 any one or more of the gears 39, 40, 45, 46 any 45 desired speed ratio may be established between shafts 38 and 59 for change speed purposes, as will readily be understood. The short shaft 38 is rotated by a sprocket 37 mounted thereon which sprocket is driven by a chain 36 through 50 a suitable sprocket 28 which is adapted to be driven from a gear 24 mounted on a drive shaft 23 from which the reels 5a to 5i are also driven.

Associated with sprocket 28 is another sprocket which is connected by chain 29 to a sprocket 30 55 on a short shaft 31 provided with a gear 32 which drives a series of gears marked generally 33, the last one of which is on a horizontal shaft 34 which extends from end to end of the machine parallel to its front and is provided at each unit 60 with suitable means for driving a spinning pump, not shown, which supplies viscose to the mass tube 35 on which the spinneret 1 is mounted. The pumps on all units are therefore driven by the same shaft and at a uniform rate of speed, 65 which may readily be varied by changing the size of any or all the change speed gears 33.

In the instant machine the reels 5a to 5i are arranged in a plurality of vertical series, on each of which the thread is subjected to the desired 70 processing treatments. Since the reels shown are of cantilever form; i. e., supported and driven from one end only, and since the thread is, by the action of the reels, advanced axially thereof, the reels may be positioned in stepped arrangement with the receiving or supported end of each 75

reel immediately below the discharge or free end of the next preceding reel. The open ends of the reels are thus presented to the operator, who may gain access thereto from the ladder 140 which may be adapted to slide across one 5 of the operating faces of the machine. This arrangement of reels provides advantages in construction of the apparatus as well as advantages in permitting access to the reels for manipulation, thread inspection, etc. Furthermore, it has 10 been found desirable to position corresponding reels in adjacent series in corresponding positions, the reels thus being disposed in a plurality of horizontal series extending longitudinally 15 of the machine.

As mentioned, reels 5a to 5i are driven from diagonal drive shaft 23, provided at various levels with take-off drives for said reels. For convenience, the shafts 23 and the drive connections therefrom to the several reels may be located at 20 one end of the machine, as shown in Figures 2 and 4. Drive shaft 23 may be driven through gear 22, mounted thereon, which meshes with gear 21 fixed for rotation to a shaft 20 which is driven from the speed reducing mechanism 19 25 from a suitable motor, not shown. Each of reels 5a to 5i is adapted to be driven from one of the gears 63 mounted along and driven by shaft 23. Gear 63 drives gears 64, 65 which correspond to the previously mentioned gears 40, 45 and, like 30 them, are mounted on an adjustable slotted bracket 66 mounted to swing around the axis of shaft 67 which is provided with a driven gear 68. Here also, by substituting a gear of different size for any one or more of gears 63, 64, 65, 68 any desired 35 speed ratio may be established.

Shafts 67 are provided at intervals with suitable take-off drive means for corresponding reels of different units in a horizontal series. The take-off drive means include spiral gears 40 similar to the gears 47, 48 and clutch members similar to the clutch members 50, 51. It will be understood that the same shaft 23 carries distributed along its length a plurality of gears 63 each of which drives a set of change speed 45 mechanism. Shafts 67 extend from end to end of the machine and at intervals are provided with means for driving the reels disposed therealong in the manner indicated above.

The reels of the present invention are preferably of the type shown in Figures 4 and 6, which reel is of the same general form and operates in the same manner as the reel shown, described, and claimed in British Patent No. 413,414. The reel shown is, however, of cantilever form in the sense that the supports for said reel are connected to it at one end only, leaving the thread-supporting bars free and open at the other end of the reel. Therefore by rotating the reel in the proper direction to cause the turns of thread 60 to travel from its driven end to its free end, the task of transferring the thread from reel to reel is materially simplified due to the absence of a shaft extension and consequent ease of manipulation of the thread by the operator.

The typical form of reel shown in these figures includes two rigid, generally cylindrical members respectively designated 80 and 81. Member 80 may be termed the concentric member because it is concentric with, fixed to, and rotates with 70 the shaft 59. Member 80 includes a body portion of generally cylindrical form with its periphery slotted to form a series of alternating bars 82 and recesses 83, the body portion being mounted upon a sleeve 84 keyed to the shaft 59 and held in 75

place thereon by a nut 85 threaded upon the end of said shaft. The other member 81 of the reel may be called the eccentric member, because while it is generally of cylindrical form it is mounted with its axis laterally offset slightly from and disposed askew or inclined to the axis of the shaft 59. The member 81 as shown comprises a head formed of inner and outer rings 87, 88, the former of which has peripheral slots to receive the bars 89. The bars are clamped between the rings 87, 88, which are held together by screws 81a. Inner ring 87, mounted on a sleeve 90 journalled to rotate upon a supporting member 91 which surrounds shaft 59, and is supported with its axis slightly offset laterally from and askew with relation to the axis of shaft 59.

Rotation of the drive shaft 59 causes concentric member 80 fixed thereto to rotate, whereupon contact of bar members 82 of concentric member 80 with bar members 89 of eccentric member 81 causes said eccentric member to rotate. The thread is thus caused to wind on the reel, the degree of the askew relation determining the lead or pitch of the turns of thread wound in generally helical form upon the reel and progressively advanced along it. With a reel of this general type any desired length of thread within reasonable limits may thus be temporarily continuously stored in a plurality of advancing turns.

Reels of the form shown in Figures 4 and 6 may be employed for each of the reels 5a to 5h inclusive, Figure 1, since it may be desirable to apply wet processing treatments to the thread while stored on these reels. However, it may be desired to dry the thread on the reel 5i before it is collected, as by cap-twister 7, in which case the reel 5i, while of the same general type and operating in the same general manner as the others, may be adapted to supply drying medium to the thread stored on the reel from the interior of the reel, as described in detail in said prior application Serial No. 7,114.

Means are provided for subjecting the thread on one or more of the reels 5a to 5h to suitable wet processing operations; to wit, means disposed above each of said reels for supplying to said reel a spray or series of small streams of processing liquid, troughs for collecting said processing liquid as it drains from the reel, and apparatus for recirculating the liquid or conducting it to the sewer. By reference to Figures 2 and 4 it can be seen that the means for applying the processing liquid to the thread on each reel comprises a suitable reagent distributor 115 positioned above each reel and supplied from a common supply manifold 113 extending longitudinally of the machine. A trough 108 may be disposed below each of the wet processing reels, to collect the liquid, which trough may be provided with a re-entrant portion 118 below each reel to allow the transfer of the thread from a higher reel to a lower reel.

Because of the arrangement of the reels in a machine in a plurality of horizontal or longitudinally extending series it is possible to have each trough served several corresponding reels in adjacent series. Each trough 108 may communicate either with a sewer, as in the case of wash water or other liquid which is to be discarded, or, as in the case of liquids which it is desired to re-use, with suitable recirculating and make-up systems. Such a system is illustrated in Figure 4, in which the drain pipes 109 from the corresponding troughs 108 along the full length of the machine communicate with a pipe 109b leading to a collecting and make-up receptacle 110, from which receptacle the liquid is pumped by pump 112 to the corresponding reagent supply manifold 113.

Various changes and modifications may be made in the apparatus illustrated as embodying the invention without departing from the spirit thereof. The invention is in no way restricted to the employment of self-threading thread-advancing reels of the form shown: other thread-advancing thread store devices may be used instead. Likewise, the thread-advancing thread store devices may be disposed in other positions with respect to the coagulating trough. It is intended that the patent shall cover, by suitable expression in the appended claims, whatever features of patentable novelty reside in the invention.

What is claimed is:

1. Apparatus for the manufacture of thread or the like comprising a longitudinally extending coagulating trough having an operating face disposed along one side thereof; means in said trough for forming a plurality of separate threads, said means being accessible from the operating face of said trough; a plurality of self-threading thread store devices of cantilever form to each of which one of said threads passes from said coagulating trough, said devices being disposed above the level of the liquid in said coagulating trough, having their axes at an angle to a vertical plane parallel to the longitudinal axis of said coagulating trough, and having their supported ends within reach from the operating face of said coagulating trough; and take-up means to which said threads pass from the unsupported ends of said thread store devices.

2. Apparatus of the character described in claim 1 in which the unsupported ends of said devices extend away from and beyond the lateral limits of said coagulating trough.

3. Apparatus of the character described in claim 1 in which the supported ends of said devices are so disposed that liquid carried over to said devices tends to return along said threads to said coagulating trough.
